US00D970693S

(12) **United States Design Patent** (10) **Patent No.:** **US D970,693 S**
Wang (45) **Date of Patent:** **** Nov. 22, 2022**

(54) **BASIN MIXER**

(71) Applicant: **JIANGXI IRONMA SANITARY WARE TECHNOLOGY CO., LTD,**
Ji'An (CN)

(72) Inventor: **Jihe Wang**, Xinyang (CN)

(73) Assignee: **JIANGXI IRONMA SANITARY WARE TECHNOLOGY CO., LTD,**
Ji'an (CN)

(**) Term: **15 Years**

(21) Appl. No.: **29/841,909**

(22) Filed: **Jun. 9, 2022**

(51) LOC (13) Cl. **23-01**

(52) U.S. Cl.

USPC **D23/238**

(58) **Field of Classification Search**

USPC D23/238-244, 252, 254-255, 257, 499;
D7/398

CPC F16K 31/602; F16K 31/605; F16K 31/607;
E03C 1/0412

(57) **CLAIM**

The ornamental design for a basin mixer, as shown and described.

DESCRIPTION

FIG. 1 is a perspective view of a basin mixer showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 shown in FIG. 2. The dash-dash broken lines in the drawings depict portions of the basin mixer that form no part of the claimed design. The dot-dash broken lines represent boundaries of the enlarged portion and form no part of the claimed design.

1 Claim, 9 Drawing Sheets
